William E. VerPlanck,
by *Albert S. Dain*
His Attorney.

UNITED STATES PATENT OFFICE.

WILLIAM EVERETT VERN PLANCK, OF ERIE, PENNSYLVANIA, ASSIGNOR TO GENERAL ELECTRIC COMPANY, A CORPORATION OF NEW YORK.

INTERNAL-COMBUSTION ENGINE.

1,347,768.

Specification of Letters Patent. Patented July 27, 1920.

Application filed November 9, 1918. Serial No. 261,761.

To all whom it may concern:

Be it known that I, WILLIAM EVERETT VERN PLANCK, a citizen of the United States, residing at Erie, in the county of Erie, State 5 of Pennsylvania, have invented certain new and useful Improvements in Internal-Combustion Engines, of which the following is a specification.

The present invention relates to internal 10 combustion engines of the type having a valve mechanism such as a fuel valve, operated by a cam through the intermediary of a member usually termed a push rod. The push rod is generally connected at one end 15 to the valve mechanism, and extends through suitable guides to a point where its other end is adjacent to the operating cam, and it is provided with a stop collar to limit its movement.

20 One object of my invention is to provide an improved structure and arrangement of push rod wherein the stop collar can be readily adjusted to give the desired length of stroke to the push rod and prevent it 25 moving inward too far when the cam moves from under it, and firmly clamped in adjusted position in such manner that there is no danger of its becoming loose.

A further object of my invention is to 30 provide an improved arrangement for lubricating all the wearing parts of the push rod such lubricating arrangement including means whereby an oil film is maintained on the fixed stop against which the stop collar 35 on the push rod strikes whereby a cushion is provided which serves to reduce the wear to a minimum and deaden the noise.

For a consideration of what I believe to 40 be novel and my invention, attention is directed to the accompanying description and the claims appended thereto.

In the drawing, Figure 1 is a view of 45 a part of an internal combustion engine embodying my invention, and Fig. 2 is a sectional view on a larger scale of the lower end of a push rod.

Referring to the drawing, 5 indicates the cylinder structure of an internal combustion engine and 6 pistons therein connected by 50 rods 7 to the crank shaft 8. In the present instance, a twin cylinder engine of the high compression type is illustrated but it will of course be understood that this is only by way of example and that my invention

may be carried out in connection with any 55 type of engine to which it is found applicable. 9 indicates a fuel valve directly operated by a lever 10 to the one end of which is connected a push rod 11, the lower end of which terminates adjacent the crank 60 shaft 8. On crank shaft 8 is a cam 12 which engages a roller 13 on the lower end of the push rod 11 to operate valve 9.

Referring now to the specific structure of the push rod it comprises two members 65 14 and 15, the member 14 being in the form of a length of rod or a tube and the member 15 being in the form of a hollow head. At the upper end of the member 14 is attached a clevis 16 between the furcations of which 70 the end of lever 10 is pivoted. The two members 14 and 15 are connected together by a link having a central taper plug 17 and threaded ends 18 and 19. Threaded end 18 is screwed into the lower end of tube 75 14 and may be fastened by a pin 20 as shown in Fig. 2. The upper end of head 15 is provided with a tapered bore 21 which receives plug 17 and just below the tapered bore it is threaded to receive the threaded 80 end 19 of the connecting link. The upper end of head 15 having the tapered bore is slotted longitudinally as indicated at 22 and is threaded on the outside to receive a stop nut 23 which forms the stop collar for the 85 push rod. When the taper plug is forced into the tapered bore by screwing the threaded end 19 down, it expands the slotted end of the head against stop nut 23 to firmly lock it into position. The lower end 90 of head 15 is enlarged and is provided with two furcations 15a between which the roller 13 referred to above is journaled.

The crank casing of the engine is indicated at 24 and as shown in Fig. 1, the lower 95 end of the push rod passes through the same. On the upper side of the crank casing is a downwardly projecting sleeve 25 through which the push rod passes. Sleeve 25 forms a guide for the push rod and at its upper 100 end it is counterbored to form a stuffing box 26 in which is a packing 27. The head 15 is located in a guide member 28 which is fixed to the crank casing 24 by rods 29, which rods also serve to hold sleeve 25 in 105 position. Between the stop nut 23 and the lower end of sleeve 25 is a spring 30 which acts to hold roller 13 in operative relation to

cam 12. There is also a suitable spring in casing 31 which closes valve 9. The enlarged lower end of head 15 is provided with a groove 32 in which is located the end 5 of a set screw 33 which serves to prevent head 15 falling into the crank case in case of breakage of links 17—18.

Referring now to the lubricating arrangement for the push rod, lubricant is supplied 10 under pressure through pipe 35 to an annular chamber 36 from the lower end of which leads a passage 37 which communicates with a slot 38 passing entirely through head 15. Leading from the interior of head 15 adjacent its lower end is a passage 39 which conveys lubricant to roller 13. This lubricates the lower end of head 15 and the roller 13. Surrounding the upper end of head 15 is an annular groove 40, the lower 20 end of which is connected to annular chamber 36 by a passage 41 through which lubricant passes to groove 40. Lubricant from groove 40 lubricates the upper end of head 15 and also overflows on to the flat surface 25 42 against which stop nut 23 strikes when the valve 9 closes, and cam 12 moves from under roller 13. This forms an oil film on surfaces 42 which serves to cushion the blow of stop nut 23 against surface 42 and also 30 to deaden the noise. To adjust the stop nut 23 relative to surface 42, the pressure of the taper plug 17 on the slotted end of head 15 is relieved by screwing the plug out of the head a little. The nut 23 can then 35 be adjusted to the desired position after which the taper plug 17 is again screwed down to expand the wall of the upper end of the head against the nut thereby locking it in its adjusted position.

40 In Fig. 2 cam 12 is shown as having moved under roller 13 to open valve 9 and stop nut 23 is spaced from surface 42. When cam 12 moves from under roller 13, spring 30 will quickly bring stop nut 23 into 45 engagement with surface 42 and it will be noted that this blow tends to drive the tapered bore at the upper end of head 15 more firmly over the taper plug 17, thus tending to further expand the slotted end 50 of the head within the stop nut 23. This

means that the operation of the engine tends to tighten the locking of the stop nut in position rather than to loosen it.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States, is:—

1. In an internal combustion engine, a 65 push rod comprising two members, one of which has a longitudinally split end with a tapered counter-bore, means for connecting the two members together comprising a taper plug which fits into said counterbore 70 and has projections which are fastened to said two members, and a stop nut which screws over said split end.

2. In an internal combustion engine, a 75 push rod comprising two members, one of which has a longitudinally split end with a tapered counter-bore, means for connecting the two members together comprising a taper plug which fits into said counter-bore 80 and has projections which are fastened to said two members, a stop nut which screws over said split end, a fixed stop against which the stop nut strikes, and means for maintaining a film of lubricant on the surface of said fixed stop.

3. In an internal combustion engine, the combination of a valve, a cam, and a push rod through which the cam actuates the valve, said push rod comprising a tube, a head having its upper end longitudinally 90 split and provided with a tapered bore, a stop nut which surrounds said upper end, and a member which connects the tube to the head and is provided with a tapered section which fits into said tapered bore to expand 95 the end of the tube within said stop nut.

In witness whereof, I have hereunto set my hand this 5th day of November 1918.

WILLIAM EVERETT VER PLANCK.
